Application November 29, 1948, Serial No. 62,468

7 Claims. (Cl. 53—93)

1

This invention relates to packaging machines and various components parts of such machines.

It is an object of this invention to provide an auger feed mechanism for that type of machine which includes means for, advancing a web of material, shearing off a sheet, forming a container from said sheet; filling said container, closing said container and discharging said filled container from the machine.

It is an object of the invention to provide a filling mechanism in which an auger delivers materials to be packaged through a punch which formed the container.

It is a further object to provide a hopper mechanism holding a six or eight hour supply of material, including an agitator for keeping the material agitated to insure uniform quantity in feeding, an auger mechanism for intermittently discharging a measured quantity of material from the hopper into a tube for filling a container located in a rotary table at the lower end of the tube, said auger mechanism being operated in timed relation with the machine to avoid spillage of the material on the rotary table.

It is a further object of the invention to provide a transmission for a filling machine which will give continuous rotation to an agitator and give intermittent rotation to an auger located at the lower end of said agitator and having its drive shaft extending down through said agitator.

It is an object to provide mechanism for rotating an auger intermittently by a clutch that is engaged by a cam that may be adjusted to vary the period of clutch engagement and thereby provide means for accurately controlling the quantity of material to be fed.

It is another object to provide a low cost filling machine resulting from forming the cylindrical sections of the hopper and the frame of the machine from one integral sheet or piece of tubing.

It is another object of the invention to provide means for packaging materials with mechanism which would be only semi-automatic in operation, wherein a single revolution clutch mechanism on the drive shaft combined with an additional clutch for controlling the intermittent rotation of the auger would provide means for the fastest operation with accurate mechanical control on the quantity of material supplied into the containers.

It is a further object to provide a conveyor mechanism for a filling machine for conveying the material from a knee-high receptacle at the base of the machine to an elevated hopper by a screw conveyor formed on a drive shaft extending from

2

the receptacle to a transmission mounted at the top of the hopper.

A fuller understanding of the nature of these and other objects of the invention will be had by referring to the following detailed description in connection with the accompanying drawings in which:

Figure 1 is a view in elevation of a packaging machine employing the invention with some parts removed and other parts shown in section to better illustrate the invention.

Figure 2 is an enlarged plan view of the transmission unit shown in Figure 1, with parts removed and others broken away.

Figure 3 is a sectional view taken along the line 3—3 of Figure 2.

Figure 4 is an end elevational view of the transmission mechanism illustrated in Figure 2 with some parts broken away and other parts omitted for the sake of clarity.

Figure 5 is a view in elevation of a filling machine employing the invention with some parts removed and other parts shown in section.

Figure 6 is a sectional view taken along the line 6—6 of Figure 5.

Referring to the drawings Figures 1, 2, 3 and 4, there is shown in Figure 1 apparatus similar to the mechanism shown in a co-pending application of Paul A. Ketchpel, Serial No. 36,225. The present invention differs from the application referred to in disclosing auger feed mechanism which is intermittently operated for filling containers rather than the metering wheel apparatus shown in the aforesaid application.

Metering wheels are provided with a cavity which fills up when rotated under a hopper and then discharges its load of material when the metering wheel is oscillated 180° to discharge its load. When packaging powderlike materials similar to common soda and other such tacky materials, the cavity in metering wheels soon loses its full capacity because these materials adhere to the bottom of the cavity and short weight takes place in the packages that are being filled.

45 This trouble is entirely removed by use of the auger mechanism herein disclosed, of which the following is a full description:

The machine is provided with frame 102 and stationary table 104. Bearing housing 134 mounted on the stationary table 104, is equipped with bearings 133 for supporting a hollow spindle 131. A Geneva cam 135 is mounted on the lower end of the hollow spindle 131 and it is caused 55 to rotate intermittently by a Geneva crank 125

which is mounted on and caused to be turned by a cam shaft 118. A rotary table 160 is mounted on the upper end of the hollow spindle 131 and rotated intermittently therewith. A number of shouldered recesses 161 are provided in the rotary work table 160 to accommodate the product sleeves 162 having flanges 163 that engage the recesses 161. The product sleeves 162 are provided with a small bore 164 at their lower end and a larger bore 165 at their upper end in which a plunger 166 is mounted for vertical reciprocation. Plunger 166 is provided at its upper end with a flange 167 that fits the larger bore 165. The plunger is also provided with a spherical seat 168 at its upper end and a ball bearing 169 at its lower end. The plunger is moved downward in the product sleeve by gravity and is caused to rise by contours on a ring cam 170 mounted on the stationary table 104.

The Geneva crank 125 and cam 135 cause the rotary work table to stop for its intermittent dwell with one of the product sleeves 162 directly over the cam shaft 118. The contour of the ring cam 170 is at its lowest point at this station and the plunger 166 is all the way down in the product sleeve 162, providing a cavity 289 in the product sleeve 162 immediately above the spherical end 168 of the plunger 166.

The container to be filled is formed at this station. The mechanism for feeding the paper web and shearing it off in single sheets will now be described. A paper feed mechanism 175 is shown mounted on the stationary work table 104 adjacent to the cavity 289 at the container forming station. It comprises a frame 176 in which an upper feed roll shaft 182 and lower feed roll shaft 183 are mounted. These feed roll shafts are provided with companion gears not shown and rubber rollers 186 and 187 for intermittently advancing a web 233 of paper or other material as they are intermittently rotated by mechanism not shown here. A lever 216 is provided on a shaft 217 which is mounted in bearings not shown in the frame 176 and is oscillated in timed relation with the machine by mechanism not shown. The outer end of the lever is connected to a paper shear blade 208. Thus the web of material is advanced over the cavity 289 in the product sleeve and a single sheet is sheared off and rests centrally over the cavity 289.

The punch for forming a container from the sheet which has been sheared from the web of material will now be described. The sliding head 140 comprising a plate 141 and a tubular shaft 142 are mounted for vertical reciprocation within the hollow spindle 131. A cam follower 143 is mounted in the lower end of the tubular shaft 142 and is provided with an upper cam roller 148 and a lower cam roller 149 not shown between which a cam 123 is mounted which had an upper and lower contour 150 and 151 not shown for reciprocating the sliding head 140. A punch 251 is suitably mounted to the sliding head and reciprocates vertically therewith. On its downward stroke it pushes the sheet of web material down into the cavity 289 to form the container.

A hopper 257 is supported on the stationary work table 104 by the upright frame members 254 in such a position that its lower discharge end is directly in line with the punch and over the cavity 289. Cross channel members 253 extend between the upright frame members 254 on which the lower end of the hopper is supported. The hopper comprises a cylindrical portion 267 and a lower conical portion 268 which is

provided with a flange 256 which rests on the cross channels 253.

A feed tube 255 is provided with a flange 356 and bolted to the under side of the hopper. If desired, the feed tube may be constructed of an upper and lower portion to facilitate assembling. It should be noted that the feed tube 255 is mounted to telescope within the hollow punch 251.

The means for controlling the supply of material to be fed from the hopper 257 through the feed tube 255 and hollow punch 251 to fill the container will now be described. In the present case, an auger mechanism which is operated intermittently in timed relation with other elements of the packaging machine comprises a vertical drive shaft 285 equipped with universal joints 283, a flexible shaft 284 and a shaft 500 extending up along the cylindrical portion of the hopper 267 and is mounted at its lower end in bearing 282. This drive shaft is driven from gearing in the base of the machine (not shown) and if desired may be brought up on the outside of the frame, but in Figure 1 we prefer to show it extending up through the sliding head 140 and the rotary table 160. The upper end of the shaft 500 extends into a transmission unit 501 mounted at the top of the hopper 257. The shaft 500 is mounted in a lower bearing 502 in the transmission housing 503 which is fastened to the hopper 257 by angles 504 and bolts 505. The shaft 500 extends upward through the transmission housing and its upper end is mounted in the upper bearing 506 in the transmission cover 507 which is illustrated best in Figures 2, 3, and 4. Shaft 500 is rotated continuously in timed relation with the rotary table 160 and other parts of the machine.

A small sprocket 508 is keyed on shaft 500 and is connected by a chain 509 to drive a large sprocket 510 which rotates an agitator mechanism located in the conical portion 268 of the hopper. The agitator mechanism comprises a tubular shaft 511 which is mounted in the lower bearing 512 on the housing 503. The large sprocket 510 is keyed to this tubular shaft 511 and lower end extends down into the hopper 257 where its lower end is supported in a channel 513 which is supported in the hopper. Below the channel 513, an agitator 514 is mounted on the tubular shaft 511. The agitator comprises a hub 515, radial arms 516, a blade 517, and a tubular extension 518 which is provided with pins or conveyor flights 519. The arms 516 and blade 517 are arranged to agitate the material in the conical section 268 of the hopper 257. The flights 519 on the tubular extension are arranged to agitate the material in the upper part 252 of the feed tube 255. This agitator mechanism is turning continually at a slow speed and insures that the material to be fed from the hopper will be prevented from arching over and that an ample supply of material will always be present at the lower end of the feed tube 255. Associated with the material supply mechanism, a helical escapement, or auger 520 is provided in the feed tube 255. It comprises flights of small diameter with a fast lead for that portion mounted in the small end 521 of the feed tube 255 and is provided with tapering flights of larger diameter and slower lead for that portion mounted in the tapering section 522 and enlarged straight upper section 523 and also a hub 524 provided with an internal thread 525. A double flight may be used at the lower end of the auger to prevent dribble

5

of free flowing materials onto the rotary work table 160 after the auger has stopped turning.

The mechanism for rotating the auger 520 during that period of time allotted to the filling of the container and stopping it quickly and holding it against rotation at other periods will now be explained. The auger 520 is screwed on an auger shaft 526 which extends up through the tubular shaft 511 and is mounted in a bearing 527 in the cover 507. It is equipped with a small sprocket 528 and is connected by a chain 529 to a large sprocket 530 which is freely mounted on the vertical drive shaft 500. The lower side of the large sprocket 530 is equipped with a clutch lining 531 with high friction qualities, like brake lining or clutch facing. A coil spring 532 is disposed between a ball bearing in the hub of the large sprocket 530 and the upper bearing 506 which normally forces the large sprocket 530 down on a brake ring 533 supported by three posts 534 secured to the lower wall of the transmission housing 503. This mechanism quickly stops the auger 520 and holds it against rotation.

A clutch 535, comprising a flange 536 and a hub 537, is splined on the shaft 500 and mounted for sliding thereon to engage and rotate the sprocket 530. A wide cam roller 538 is mounted on a stud 539 screwed in the hub 537 of the clutch 535. A sector of a ring cam 540 is provided on the bottom wall of the transmission housing 503 for raising the clutch 535 and causing it to engage the clutch lining 531 and turn the large sprocket 530. This will cause the small sprocket 528 on the auger shaft 526 to rotate several revolutions according to the length of the sector of ring cam used.

The amount of rotation of the auger may be adjusted by making the length of the sector of the ring cam 540 variable. This may be accomplished by providing a rigid sector 541 being fixed with the transmission housing 503 and supplemented with a movable ring cam sector 542 as shown best in Figures 2 and 3. The movable cam sector 542 is welded to a sliding block 543 mounted in an arcuate slot 544 cut in the bottom wall of the housing 503.

The sliding block 543 is provided with a clamping bolt 545 which is provided with a knurled knob 546. An eye bolt 547 is mounted on the clamping bolt 545 having its threaded end engaging a cam adjusting knob 548 mounted in the pivoted bearing 549 to the bottom wall of the transmission housing 503. Thus upon unscrewing the clamping bolt 545 the movable cam sector 542 can be shifted by the cam adjusting knob 548 to lengthen or shorten the length of the sector of ring cam 540 as desired, to regulate the number of revolutions that the auger will turn to control the amount of material which the auger will deliver from the feed tube 255. The maximum length of the ring sector, of course, must not be so long as to exceed the period of dwell which is given to the rotary work table 160. Furthermore, the beginning and end of the ring sector must be properly positioned to be in time relation with the movement of the rotary table 160 to prevent spillage of materials thereon.

Chain tightening rollers 560 are mounted on levers 561 which are in turn mounted on a shaft 562 screwed into the bottom wall of the transmission housing 503 at its lower end and assembled in bracket 563 welded to the wall of the transmission unit 501 at its upper end. A spring 564 is anchored to a clip 566 on the opposite side wall of the transmission housing 503. The other end

6

of the spring is fastened to a wire 565 having a loop at its center and its two outer ends fastened to the two levers 561 supporting the chain tightening rollers 560. Thus the spring 564 pulls each roller 560 tight against the chains 509 and 529 independently of the other to take up the slack as the chain may become loose.

From the foregoing it should be readily understood that we have shown and described mechanism which will fulfill the objects of the invention relating to rotating the auger feed with intermittent motion and in time relation with the machine shown in Figure 1.

The same mechanism as heretofore disclosed can be used to advantage in that type of packaging machine usually referred to as a filling machine. Such a machine is shown in Figures 5 and 6 in which the frame of the machine 575 comprises of an upright cylinder 576. A base ring 577 is welded to the lower part of the frame 575. An opening 578 is cut out in the cylinder 576 to provide a support for a work table 579 being welded in the upright cylinder 576. That portion of the upright cylinder 576 above the opening 578 may be used to advantage for the cylindrical section 580 of an overhead hopper 581. The lower portion 582 of the overhead hopper 581 may comprise a conical section 583 welded to the cylindrical section 580. The conical section 582 may also be provided with a flange 584 at its lower end. A feed tube 585 may be secured to the flange 584. The feed tube 585 may comprise a large diameter 586 at its upper end and a small diameter 587 at its lower end. An auger 591 is mounted in the feed tube 585. It is rotated by an auger shaft 592 through the transmission unit 501 mounted on the top of the hopper 581. The construction of this transmission unit is similar to that shown in Figures #2, #3 and #4 and as explained above has mechanism for operating the auger intermittently. The continuous rotating drive shaft in the transmission unit extends down along the back of the frame 575 to a knee high hopper 594 which includes the chute 595. The vertical shaft is housed in a U-shaped conduit 596 secured to the upright cylinder 576 and extending from the lower portion of the hopper 594 to an aperture 597 in the side wall of the cylindrical portion 580 of the hopper 581.

Conveyor flights 600 are provided upon the vertical shaft 593 and upon rotation of this shaft materials poured into the knee-high hopper 594 will be conveyed to the hopper 581, eliminating the strenuous labor, mess, dangers of filling a high hopper with the use of stepladders, etc.

Vertical shaft 593 extends through the lower wall of the knee-high hopper 594 into a gear box 601. The gear box is provided with a pair of bevel gears 602. One such gear is mounted on the lower end of the vertical shaft 593 and the other beveled gear is mounted on a horizontal shaft 603 mounted on the bearings 604 and 605.

Preferably the inner hub 606 of a well known one-revolution-clutch 607 is keyed to shaft 603. The outer housing 608 of the clutch 607 is mounted for continuous rotation on the shaft 603. A trip cam 609 provided with a stop lug 610 is mounted to the inner hub. The stop lug 610 strikes against the end of a trip lever 615 pivoted on a pin 616 in the frame 575 at the end of each revolution when operated as a single-revolution clutch and disengages the driving outer housing 608 from the inner hub 606. The

weight of the trip lever tends to return it to a position where it will disengage the clutch.

A link 617 is connected to the trip lever 615 between its ends and also to a bellcrank 619 pivotly mounted to the frame by a bolt 620. A 5 rod 621 connects the bellcrank 619 and a second bellcrank 622 which is pivoted to the frame and is equipped with a foot pedal 623 which extends out through an opening in the frame 575 for manually controlling the engagement of the 10 clutch.

A ratio motor 624 is provided with a variable pulley 625 and is mounted for adjustment in the frame 575 by the hand wheel 626. A belt 627 is provided between pulley 625 and a slow speed pulley 628 which is mounted on and drives the outer housing 608 of the clutch 607 according to the speed at which it is desired to operate the machine. It should be readily understood that various size feed tubes 585 and augers 591 may be used to fill larger or smaller containers. Also that the filling machine just described may be equipped with complete automatic mechanism for forming containers and moving them in and out of engagement with the feed tube or, if desired, a less expensive machine can be provided with a corresponding smaller rate of production by utilizing a single-revolution-clutch and automatic equipment to perform only certain steps in the process for 20 semi-automatic operation.

Thus it will now be apparent that we have disclosed the construction for a machine which may be used to accurately feed uniform measured quantities of material from a hopper into containers formed by the machine or containers presented manually thereto.

The construction disclosed and described represents the preferred and commercially used form of the invention, but various changes of detail may be made without departing from the scope of the invention.

We claim:

1. A packaging machine of the character described, comprising a frame, a worktable mounted for intermittent rotation on said frame, spaced dies provided on said worktable, plungers mounted in said dies for discharging containers therefrom, a sliding head mounted for reciprocating movement above said table, a hollow punch mounted on said sliding head and positioned at a work station, means for moving said worktable intermittently to place the spaced dies in sequence below the punch at the work station during the dwell period of said worktable, sheet feeding mechanism arranged to supply a sheet of container material over the die positioned at the work station during the dwell of said worktable, power mechanism incorporated in said machine for driving same and reciprocating said sliding head up and down, a hopper mounted above said worktable for supplying material to be packaged through said hollow punch, a feed tube extending from said hopper to said hollow punch, an auger in said feed tube for delivering material to the punch, said power mechanism including a drive shaft extending to said hopper, means associated with said drive shaft and said auger for rotating said auger while said punch is engaging said die and while the movement of said reciprocating sliding head is causing said punch to engage the die on the stationary worktable at the work station, means for actuating said plunger in said dies to remove the containers

therefrom as the table moves them successively to another station.

2. In combination, in a packaging machine, a frame, a worktable mounted for intermittent rotation on said frame, spaced dies on said worktable, a sliding head arranged for vertical reciprocation in said worktable, a discharge tube mounted on said sliding head and positioned at a work station, means for moving said worktable intermittently to place one of said dies in sequence below the discharge tube at the work station during the dwell period of said worktable, power mechanism incorporated in said machine for driving same and reciprocating said sliding head up and down in said worktable, a hopper mounted above said worktable for supplying material to be packaged to said discharge tube, a feed tube mounted rigid with said hopper and extending from said hopper to said discharge tube and engaging therein, an auger in said feed tube delivering material to the discharge tube, said power mechanism including a drive shaft extending to said hopper, and means associated with said drive shaft and said auger for rotating said auger while said discharge tube is being actuated and while the movement of said reciprocating sliding head is causing said discharge tubes to engage the die which is positioned at the work station during the dwell period of said worktable.

3. In combination, in a packaging machine, a frame, a worktable mounted for intermittent rotation on said frame, spaced dies on said worktable, a sliding head arranged for vertical reciprocation in said worktable, a discharge tube mounted on said sliding head and positioned at a work station, means for moving said worktable intermittently to place one of said dies in sequence below the discharge tube at the work station during the dwell period of said worktable, power mechanism incorporated in said machine for driving same and reciprocating said sliding head up and down in said worktable, a hopper mounted above said worktable for supplying material to be packaged to said discharge tube, a feed tube mounted rigid with said hopper and extending from said hopper to said discharge tube and engaging therein, an auger in said feed tube delivering material to the discharge tube, said power mechanism including a drive shaft extending to said hopper, auger drive means provided between said shaft and said auger, said auger drive means including a clutch, a cam for engaging the clutch while the movement of said reciprocating sliding head is causing the feed tube to approach the die positioned at the work station during the dwell period of the worktable and means for adjusting the period of clutch engagement.

4. In combination, in a packaging machine, a frame, a worktable mounted for intermittent rotation on said frame, spaced dies on said worktable, a sliding head arranged for vertical reciprocation in said worktable, a discharge tube mounted on said sliding head and positioned at a work station, means for moving said worktable intermittently to place one of said dies in sequence below the discharge tube at the work station during the dwell period of said worktable, power mechanism incorporated in said machine for driving same and reciprocating said sliding head up and down in said worktable, a hopper mounted above said worktable for supplying material to be packaged to said discharge tube, a feed tube mounted rigid with said hopper and

extending from said hopper to said discharge tube and engaging therein, an auger in said feed tube delivering material to the discharge tube, said power mechanism including a drive shaft extending to said hopper, a drive mechanism connecting said power shaft and said auger which is mounted in a transmission housing located at the top of the hopper, said drive mechanism comprising a driving member freely mounted on the power shaft and having a friction surface on its bottom face, a brake ring provided in said transmission housing on which a portion of the friction face of the driving member normally rests, and a clutch member provided on said power shaft in said transmission for engaging the friction face of said driving member to rotate the auger while said discharge tube is approaching said dies and while said dies are positioned in said work station during the dwell period of said intermittently moved worktable.

5. In combination, in a packaging machine, a frame, a worktable mounted for intermittent rotation on said frame, spaced dies on said worktable, a sliding head arranged for vertical reciprocation in said worktable, a discharge tube mounted on said sliding head and positioned at a work station, means for moving said worktable intermittently to place one of said dies in sequence below the discharge tube at the work station during the dwell period of said worktable, power mechanism incorporated in said machine for driving same and reciprocating said sliding head up and down in said worktable, a hopper mounted above said worktable for supplying material to be packed to said discharge tube, a feed tube mounted rigid with said hopper and extending from said hopper to said discharge tube and engaging therein, an auger in said feed tube delivering material to the discharge tube, said power mechanism including a drive shaft 40 extending to said hopper, driving mechanism connecting said power shaft and said auger, a transmission housing in which said driving mechanism is mounted, said drive mechanism comprising a driving member freely mounted on the power shaft and having a friction surface on its face, a brake member provided on said transmission housing against which the face of the driving member is normally restrained, a clutch member splined on said power shaft, a cam roller provided on said clutch member, and a cam ring sector supported by said transmission housing for contacting the roller and engaging the clutch during a portion of the cycle of the machine

whereby the application of the brake to stop the auger is simultaneous with the disengagement of the clutch member, and the withdraw of the discharge tube way from the die which is positioned at the work station during the dwell period of the intermittently moved rotary table.

5. In combination, a frame, a rotatable worktable mounted on said frame and provided with a plurality of dies equally spaced along its perimeter; driving means connected to said worktable to intermittently rotate the same and sequentially position each die successively at a location defined as a container forming station; feeding means for feeding a sheet of container material over each die when said each die is positioned at said forming station; a reciprocatable hollow punch supported by said frame and positioned at said forming station; means to reciprocate said punch to a first position in which said punch forces said sheet into each die as it is moved to the forming station and forms a container therein and then to a second position in which said punch is withdrawn from said die; a hopper containing filler attached to said frame and positioned over said punch, said hopper being provided with a filler discharge orifice; a rotatable helical escapement mechanism connected between said orifice and the top of said punch to feed filler through said punch onto said sheet when said mechanism is rotated; and means in timed relation with said punch reciprocation means to rotate said mechanism within successive intervals each of which is initiated by the positioning of a die at the forming station and terminated by the withdrawal of the punch from said die.

7. The combination as set forth in claim 6 wherein said escapement mechanism comprises an auger provided with helical flights of varied dimension advancing along the filler feed path.
